UNITED STATES PATENT OFFICE.

ERNST G. HELANDER, OF PHILADELPHIA, PENNSYLVANIA, ASSIGNOR TO UNITED STATES CAST IRON PIPE & FOUNDRY COMPANY, OF BURLINGTON, NEW JERSEY, A CORPORATION OF NEW JERSEY.

ANNEALING FURNACE.

Application filed June 18, 1922. Serial No. 568,702.

To all whom it may concern:

Be it known that I, ERNST G. HELANDER, a citizen of the United States of America, and resident of Philadelphia, county of Philadelphia, State of Pennsylvania, have invented a certain new and useful Improvement in Annealing Furnaces, of which the following is a true and exact description, reference being had to the accompanying drawings, which form a part thereof.

My invention relates to annealing furnaces such as are used in annealing iron pipes cast in metal molds. In such furnaces it is desirable that the pipes should be revolved while being annealed and supporting rollers are used which are liable to become so cooled as to carry away too much heat from the pipes supported upon them and then prevent the proper annealing of the pipes. The object of my invention is to provide means for supporting the rollers which will prevent the undue cooling of the rollers and my invention consists in the construction of the furnace and of roller supporting and enclosing boxes insertable in the bottom of the furnace which is illustrated in the drawing in which—

Figure 1 is a longitudinal sectional elevation of the furnace on line 1—1 of Fig. 2. Figure 2 is a horizontal section on line 2—2 of Fig. 1, and

Figure 3 is a cross section on line 3—3 of Fig. 1.

A is the furnace having an opening A¹ for the insertion of the pipes, outlets B for the escape of furnace gases and inlets C for the gas and air. D is a door closing opening A¹. E and E¹ are transversely extending openings or chambers formed through and below the bottom of the furnace and preferably extending through its side walls as shown at E². E³, E⁴ and E⁵ are shaft chambers extending below the bottom of the furnace and through its rear wall. The chambers E³ and E⁴ are covered as indicated at E⁶. F, F, are iron boxes having water cooled side walls F⁸ in which are formed bearings F², F², etc. for the roller shaft K. F¹ indicates the water jackets for cooling the side walls. G indicates a heat insulating wall built over the inner walls and bottom of the boxes F and

I, I, etc., indicate rollers on which the boxes F are supported and by means of which the boxes can be easily inserted and removed from the chambers E and E¹.

K, K, etc. are shafts supported in the water cooled bearings F² of the boxes F and supporting the rollers or wheels L, L, etc. on which the pipes N are supported in the furnace. M, M, etc., are worm wheels attached to the ends of shafts K and driven by a worm M¹ on shaft M² to which shaft is attached gear M³ driven by a pinion M⁴ on the shaft M⁵ of a motor M⁶.

In operation the water jackets F¹ which are necessary to keep the bearings F² sufficiently cool tend to draw heat from the shafts K and supporting rollers L and tend also to cool the insides of the boxes F in which the greater portions of the rollers L are at all times enclosed and which form pockets into which the hot gases of the furnace do not penetrate. By lining the inside of the boxes with a non-conducting wall G I prevent the undue cooling of the inside of the boxes and of the rollers L and maintain the rollers at a sufficiently high temperature to prevent them from so cooling the portions of the pipes with which they contact to such an extent as will interfere with proper annealing. When it is desired to remove the boxes F for repairs, the rollers L are detached from shafts K and the shafts drawn out of their bearings in the boxes F and, of course, out of the hubs of rollers L. The boxes can then be easily removed and replaced.

Having now described my invention, what I claim as new and desire to secure by Letters Patent, is:

1. In an annealing furnace for pipes having transverse chambers extending through and below the furnace bottom in combination with open topped boxes situated in said chambers having water cooled shaft bearings in their side walls and non-conducting linings on the inside of their water cooled walls, shafts extending through the boxes and supported on their water cooled bearings and pipe supporting and rotating rollers secured to the shafts between the box walls.
2. In an annealing furnace for pipes having transverse chambers extending through

and below the furnace bottom and through a side wall or walls of the furnace, in combination with open topped boxes situated in said chamber having water cooled shaft 5 bearings in their side walls and non-conducting linings on the inside of their water cooled walls, said boxes being adapted to

be inserted and removed from said chamber through the openings in the furnace wall, shafts extending through the boxes and supported on their water cooled bearings and pipe supporting and rotating rollers secured to the shafts between the box walls. 10

ERNST G. HELANDER.
